FLOWER HOLDER

Paul F. K. Erbguth, 120 Station Road, Great Neck, N.Y.

Filed July 6, 1964, Ser. No. 80,721

Term of patent 14 years

(Cl. D35—3)

I claim:

The ornamental design for a flower holder, as shown.
